UNITED STATES PATENT OFFICE

THOMAS H. SEELY, OF MELROSE, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed December 10, 1929. Serial No. 413,093.

This invention relates to lasting machines of the type which operate progressively in a step-by-step manner upon the shoe.

In machines of this type a gripper is actuated to grip or pull and updraw the upper material and to overdraw or lay it upon the insole, and a wiper is given movement to engage the upper material and wipe it into lasted position upon the insole. The upper material is secured in such position by tacks which are fed into a tack pocket in the wiper prior to each operative movement thereof and are driven by tack driving means at the conclusion of the wiper advance. Suitable gauges are provided for locating the shoe in the proper transverse position with respect to the instrumentalities of the machine. On account of the difference in the contour of the last at various points in its periphery, it has been the practice to employ a thin edge gauge at some parts of the shoe and a thick or bunter-edge gauge at others. Where the contour of the last will permit, the operator prefers to use the bunter gauge because its more extended face is easier to find and follow with the shoe and because it is also effective in holding in position the upper material as updrawn by the gripper.

Machines of this type are also provided with mechanism for presenting either long or short tacks. The added thickness of the upper material supplied by the toe stiffener makes it desirable to employ long tacks at this part of the shoe and the same is true where the thickness of the insole material is increased by a reinforcement. On the other hand, good lasting requires the use of short tacks in the forepart of the shoe. In machines of this type as heretofore constructed, the edge gauges have been so related to the tacking mechanism that only certain combinations of gauge and tack supply have been available. For example, in such machines it is possible to supply long tacks only when the bunter gauge is operative and this has prevented the employment of long tacks in a reinforced shank where they are otherwise desirable. From one standpoint, my invention consists in a lasting machine having tack-supplying and gauge mechanism organized

to permit a greater flexibility of correlation than heretofore, so that the operator may at will in the lasting operation, employ either short or long tacks with one or the other of the gauges. In a more specific aspect, my invention provides for the first time an organized machine having an automatically shifting bunter gauge organized to permit the employment of long tacks while the bunter gauge is maintained in retracted position and the thin edge gauge is effective.

My invention contemplates also novel mechanism for controlling the presentation of the bunter gauge and of the tack raceways such that the operator may secure conveniently, and without interrupting the lasting operation, whatever combination of gauge and tack delivery he may desire in the particular part of the shoe which he is presenting to the machine in lasting position. This I accomplish in the machine herein shown by providing a controlling device, such as a treadle, and mechanism so designed that one depression and release of the treadle will organize the machine for lasting with short tacks and the bunter retracted so that the thin edge gauge is effective; a second depression and release of the treadle will organize the machine for lasting with long tacks with the bunter gauge effective; while a continued depression of the treadle will organize the machine for lasting with long tacks with the bunter retracted and the thin edge gauge effective; and finally, the release of the treadle after such continued holding will organize the machine for lasting with short tacks with bunter retracted.

As herein shown, I accomplish the desired results by utilizing a power-driven part of the machine as an actuator for a bunter shifting member and for a raceway shifting member. Mechanism is interposed between the actuator and these shifting members which may be effectively connected to the actuator in any cycle of the lasting machine selected by the operator, and when so connected the shifting members are moved, tending to shift both the raceway and the bunter from the positions which they then occupy. The actual

movement of both shifting members, however, is under manual control, as by a treadle, so that the operator may delay the shifting of the bunter gauge or the raceway for any desired number of lasting cycles, during which the machine will continue to operate without change of conditions.

As herein shown, safety means are provided for preventing the establishment of an effective connection with the power-operated actuator except when the parts of the lasting machine are properly positioned for the operation of the parts affected thereby. For example, the position of the raceway should not be changed while the tack separator is open, and this contingency is prevented by safety mechanism which prevents the full operation of the treadle control mechanism of the machine except when the separator is closed.

These and other features of the invention will be best understood and appreciated from the following description of a preferred embodiment thereof, selected for purposes of illustration and shown in the accompanying drawings, in which

Fig. 1 is a view of the machine in side elevation;

Fig. 2 is a plan view of the treadle mechanism with parts of the column broken away;

Fig. 3 is a view in side elevation, on a larger scale, of the lower part of the machine head;

Fig. 4 is a fragmentary view of a portion of the swing piece and related parts;

Fig. 5 is a plan view, partly in section, of the raceway and gauge controlling mechanism with parts in position corresponding to Fig. 3, that is to say, with the bunter gauge back and the raceway in position for delivering short tacks;

Fig. 6 is a similar plan view in section on the plane 6—6 of Fig. 3;

Figs. 7 and 8 are fragmentary views in perspective of portions of the raceway and bunter gauge controlling mechanism;

Fig. 9 is a plan view similar to Fig. 5 but showing the parts in position for delivering long tacks;

Fig. 10 is a view in perspective of the swing piece; and

Fig. 11 is a view similar to Fig. 9 but with the bunter gauge advanced.

The general organization of the machine is best shown in Fig. 1 where a head 10 is represented as mounted in the upper end of a column 11, of which only a portion is shown. Journaled in the head 10 is a horizontal shaft 12 provided with a driving pulley 13 at its rear end and carrying the cams from which the operative movements of the machine are derived.

The instrumentalities of the machine will be briefly referred to, but since individually they correspond to similar parts of the well-known hand method lasting machine no de-

tailed description is necessary here. A gripper 14 is given the usual closing, updrawing and overdrawing movements for engaging the upper stock and carrying it over the bottom of the last. The shoe bottom is held against a fixed but adjustable rest 15 with its side positioned against one or the other of two edge gauge, a thin edge gauge 16 or a thick edge gauge or bunter gauge 17. A reciprocating wiper 18 is provided to wipe the tensioned upper into lasted position upon the shoe bottom and a tack is fed in each cycle of the machine from one or the other of two raceway channels 19 and 20 to a pocket in the wiper by which it is carried into position to be driven by a driver 21.

The wiper 18 is carried in the forward end of a slide 43 mounted in a horizontal guide-way formed in the machine head 10. The slide has an upwardly extending arm provided with a cam roll 44 arranged to run in a cam 45 on the shaft 12, the cam being shaped to impart a complete reciprocation to the slide in each cycle of the machine. Beside operating the wiper 18 to wipe the stock over the bottom of the last and presenting a tack in driving position, the slide 43 is utilized to actuate other mechanisms, as will appear hereinafter.

The gripper 14 is carried at the lower end of a gripper bar 30 which is mounted at its upper end in a forked lever 29 pivotally mounted upon a transverse stud 28 for vertical oscillation to give the gripper the required updrawing movement. The gripper bar is controlled at its lower end by a train of mechanism actuated by a cam 32 on the shaft 12 to give the gripper the required overdrawing movement. An auxiliary horizontal shaft 33 is connected to the gripper bar through a vertical lever 34 and a rack, not shown, and is rocked by connections with the shaft 12 to impart a twisting movement to the gripper and this is controlled by the operator through the vertical shaft 27, the yoke 25 and collar 26 on the shaft 33, all as shown in my prior Patent No. 1,623,135, granted April 5, 1927.

The driver 21 is set in the lower end of a driver bar 42 arranged to slide in a driver bar carrier 40. The carrier is journaled to swing on trunnions 41, one of which is shown in Fig. 1. The slide 43 is provided at its forward end with an adjustable stop screw 46 which, as the slide is advanced, engages the driver bar carrier 40 and swings it forwardly over the shoe bottom and positions the driver in line with and above the tack pocket of the wiper 18 so that, when tripped, the driver will act to drive the tack through the pocket into the shoe.

In Figs. 1 and 3 the machine is shown with its parts located at an intermediate position in the cycle of the machine. The gripper 14 is represented as having closed upon the

stock, completed its updrawing movement and substantially completed its outward over-drawing movement. The driver 21 has been lifted to its uppermost position and has been moved outwardly with the wiper 16 as the latter advances from its tack-receiving position, which is in line with and beneath the passage in the separator 50. The raceway has been moved to bring the channel 19 for short tacks into register with a tack passage 51 in the separator. With the parts in the position shown in these figures, the machine will repeat without variation its usual functions, delivering short tacks from the raceway.

15 Proceeding now to a description of the mechanism with which the present invention is more particularly concerned, it will be understood first that the raceway includes two raceway channels 19 and 20 and that these 20 may be included in one raceway member or may be assembled so that their delivery ends are located in parallel spaced relation, as shown in Fig. 5, and capable of simultaneous movement to bring either channel into registration with the tack passage 51 of the separator 50. In the machine herein illustrated, both channels are formed in a single raceway member and this is pivotally mounted at a point remote from its delivery end so that 25 in the limited movement imparted thereto the ends of the channels 19 and 20 travel in a substantially straight path. Short tacks are supplied to the outer channel 19 and long tacks to the inner channel 20 from tack pots of 30 usual construction. Movement is imparted to the raceway by a link 52 having an adjustable extension 53 which makes a ball and socket connection with the raceway member. The link 52 at its other end is pivotally connected to a yoke 54 which is suspended upon a screw 55 threaded into an arm 56. The arm 56 is loosely mounted upon a vertical pin 57 projecting upwardly from a stationary bracket 58 secured to or forming a part of the 35 frame of the machine head. The arm 56 is provided with a horizontally extending socket for the reception of a compression spring 59 which presses always against the end of the yoke 54 and holds it in contact with the back of the pin 55, as shown best in Fig. 40 6. Near the outer end of the arm 56 is a downwardly projecting pin 60 to which is secured one end of a tension spring 61, the other end being secured to an upstanding pin 55 62 set in a bell crank lever 63 mounted to swing about the pin 57 upon which the arm 56 is also journaled. The spring 61 thus tends always to swing the arm 56 in a counter clockwise direction, moving the link 52 toward the right, as seen in Fig. 5, and holding the raceway channel 19 for short tacks in registration with the tack passage 51 of the separator.

45 The position of the arm 56 in swinging in a counter clockwise direction under the actua-

tion of the spring 61 is determined by a yoke having an upper arm 70, a lower arm 71 and a boss 72 projecting from its intermediate portion which engages a lug 49 projecting from the hub of the arm 56. This is best shown in Fig. 8, from which it will also be apparent that the arms 70 and 71 of the yoke are journaled to swing upon the vertical pin 57, the upper arm 70 of the yoke being located immediately above the arm 56 to which the link 52 is connected.

50 A pin 73 projects upwardly from the upper arm 70 of the yoke and constitutes a pivotal connection with a horizontally disposed yoke 74, best shown in Fig. 5. The yoke 74 straddles the upright shaft 27 and is guided in its movement by a roller 75 arranged to turn freely on the vertical shaft. Upon the lower face of the yoke 74 are arranged two spaced cam rolls 76 and 77 which engage between them a three-arm or star cam 78 which is also journaled upon the vertical shaft 27. The rotation of the cam 78 is effected a step at a time and causes the yoke 74 to move back and forth and, consequently, to swing the yoke 70 about the axis of the pin 57. It will be understood, however, that the yoke 74 is not intermittently oscillated in each cycle of the machine but remains at rest except when the operator takes appropriate steps to insure its actuation.

55 The shaft 27 has also journaled upon it a ratchet disk 80, see Fig. 6, immediately below the three-arm cam 78. The ratchet has six teeth and six flat lands, and is held against reverse movement by a locking pawl 81 pivoted at 82 upon a stationary part of the machine head and urged toward the ratchet disk by a tension spring 108, to be referred to later. The ratchet disk 80 also cooperates with a dog 83, pivotally mounted upon a vertical pin 84 projecting from a boss on the slide 43. The dog has a rearwardly extending arm 85, as shown in Fig. 5, which is acted upon by a compression spring located in a boss 86 projecting outwardly from a stationary but adjustable arm 87 secured to the frame of the machine head. The dog 83 is thus at all times pressed against one of the lands of the ratchet disk 80 and in the normal operation of the machine slides back and forth in contact with the land as the slide 43 is reciprocated. When it is desired to have the dog 83 turn the ratchet 80, it is necessary to impart to the ratchet a slight rotary movement in a clockwise direction to advance one of the ratchet teeth into the path of the dog 83. The mechanism for effecting this result is under the control of the operator and will now be described.

60 Beneath the ratchet disk 80 on the shaft 27 is pivotally mounted a swing piece 100, shown separately in Fig. 10. This is of irregular shape and is provided with a boss 101 from which projects a downwardly ex-

tending stud 102. The piece 100 is swung in a counter clockwise direction by a tension spring 103 secured to the stud 102 at its front end and at its rear end to a pin 137 projecting upwardly from a hook link 136, to be presently described. The swing piece 100 is moved in the opposite direction and in opposition to the spring 103 by a link 104, pivotally mounted upon the outer end of an arm 10 130.

The swing piece 100 has a radial arm or barrel 105 in which is mounted a spring pawl 106 designed to cooperate with the ratchet disk 80 and to rotate the latter in a counter 15 clockwise direction sufficiently to position one tooth of the ratchet disk in the path of the dog 83 when the swing piece 100 is rocked. A pin 107 projects upwardly from the hub of the piece 100 and serves as anchorage for 20 the other end of the tension spring 108 which holds the locking pawl 81 against the ratchet. The swing piece 100 also has an upright boss 109 in which is mounted an upwardly yielding dog 110 which normally projects below 25 the surface of the swing piece, as shown in Fig. 4, in position to engage a roller 112 mounted upon the arm 56, already described as carrying the raceway shifting link 52. When, therefore, the swing piece 100 is 30 moved into the path of the roller 112, the link 52 is locked in extended position and the raceway held in position to deliver long tacks from the raceway channel 20.

The swing piece 100 is provided with a 35 second upstanding boss 114, in which is mounted a downwardly yielding dog 115 which cooperates with a safety lever 116 pivotally mounted upon a vertical stud 117 projecting from a stationary part of the frame. The lever 116 is arranged to be 40 swung back and forth by a segment lever 118 pivotally connected to the inner end of the lever 116 and meshing with rack teeth cut in the side of the slide 43, as shown in Fig. 6. The safety lever 116 has a curved downwardly extending flange on its lower surface which stands in the path of the dog 115 while the slide 43 is in its forward position and while the tack separator is open. It 45 thus acts positively to prevent the swing piece 100 from being moved and the raceway shifted except when the slide 43 is retracted and the separator closed.

Before proceeding to a description of the 50 mechanism for moving the swing piece 100 and the effect of such movement, the bunter gauge mechanism will be first described in order that its correlation to the raceway shifting mechanism may be apparent. The 55 bunter 17 is pivotally mounted in the slide 90, arranged to be moved inwardly and outwardly in inclined ways formed in a stationary arm 91 secured to the frame of the machine head. The arm 91 is extended to form the 60 thin edge gauge 16 and when the bunter gauge

17 is advanced to the outward limit of its travel it occupies a position in registration with and immediately beneath the gauge 16, as indicated by dotted lines in Fig. 3. The slide 90 is connected at its rear end to a forked link 92, which, in turn, is connected to a bell crank lever 93 pivotally mounted upon a stud 94 projecting downwardly from a part of the arm 91, as shown in Fig. 7. The inner end of the bell crank lever is connected through 70 a link 95 to the bell crank lever 63 journaled to swing upon the lower end of the vertical pin 57 and being forked to provide spaced bearings upon the pin 57. The outer arm of the bell crank lever 63 carries the upwardly projecting pin 62 to which the other end of the tension spring 61, already mentioned, is connected, so that the bell crank lever 63 is urged at all times to swing in a clockwise direction and to advance the bunter gauge 17 to 75 its forward limit.

The limiting position of the lever 63 and the bunter gauge is determined by a short inwardly projecting arm 64 on the lever 63 which engages the inner face of the yoke 70—71. It will be apparent, therefore, that if the latter yoke is moved in a counter clockwise direction, as seen in Fig. 8, the bell crank lever 63 will be moved in a direction to retract the bunter gauge. The proportion of the parts is such that a limited swinging movement of the yoke 70—71 moves the bunter edge gauge shifting mechanism sufficiently to cause the latter to travel from one to the other limit of its path.

The mechanism by which the swing piece 100 is controlled by the operator will now be described. The arm 130 is fast upon the upper end of a vertical rod 131 journaled at its upper end in a stationary bracket projecting from the rear of the machine head. The arm 130 carries an adjustable stop screw 132 cooperating with a stationary abutment 133 on the frame to limit its movement in a clockwise direction about its axis. At its free end the arm 130 carries a stud 134 to which the link 104 is pivotally connected and to which is also connected the hook link 136 carrying the stud 137, to which the rear end of the spring 103 is connected. At its free end the hook link 136 is guided between ears 138 projecting outwardly from the body of the yoke 70—71 so that the hooked end of the link is positioned at all times to engage the stud 62 on the bell crank lever 63 which controls the shifting of the bunter gauge. The spring 103 has the double function of holding the hook link 136 inwardly in operative relation to the stud 62 and of holding the rear end of a slot in the link 104 normally against the stud 102 of the swing piece 100. Under certain circumstances, however, the swing piece 100 can be swung against the tension of the spring 104 so that the end of the slot in the link 104 is carried away from the stud 102.

The vertical rod 131 is journaled at its lower end in bearings in a bracket 140 secured to the column 11 and provided also with bearings for the lower end of the vertical shaft 27, 5 as shown in Fig. 2. The rod 131 has adjustably secured to it above its lower bearing a cross arm 141 connected at one end to a tension spring 142, tending at all times to turn the rod 131 in a clockwise direction. At its 10 other end, the cross arm is connected through a universal joint to a link 143 which extends forwardly and downwardly and is connected at its forward end to a treadle 144. The treadle 144 is located at the left side of the 15 column and is arranged for vertical movement whereby the rod 131 may be turned in opposition to the spring 142 to move the arm 130 outwardly or in a clockwise direction.

Having described the mechanism of the 20 machine herein shown, the manner of its operation will now be set forth, and for this purpose it will be assumed that the machine is to be employed in all round lasting a McKay shoe having a thin insole reinforced in 25 the shank and heel part with leather or fibreboard. For such work the operator desires to employ long tacks about the toe of the shoe on account of the added thickness of the toe stiffener in the upper material and to 30 position the shoe by the bunter gauge. Proceeding along the forepart, the operator desires to employ short tacks and to gauge the work by the thin edge gauge. Reaching the shank part where the reinforcing material 35 152 is first encountered, the operator desires to employ long tacks on account of the added thickness of the reinforcing material in the sole and to position the shoe by the thin edge gauge. Passing about the heel seat, the long 40 tacks are still employed but the bunter gauge is again relied upon in positioning the shoe. Passing into the shank on the second side of the shoe, the long tacks are maintained but the bunter gauge is retracted. Reaching the 45 forepart on the second side of the shoe, short tacks are again employed and the shoe is positioned from the thin edge gauge. Finally, again reaching the toe, the bunter is brought forward and the lasting operation finished 50 employing long tacks again.

The parts of the machine are shown in Figs. 1, 2, 3 and 5 with the bunter gauge retracted and the raceway positioned to deliver short tacks. The raceway is so positioned 55 because in a subsequent cycle of the machine the three-arm cam 78 has been turned to move the yoke 74 to the inner limit of its travel, swinging the yoke 70 in a counter clockwise direction to the limit of its oscillation and permitting the spring 61 to swing the arm 56 in the same direction, retracting the link 52 and moving the raceway channel 51 60 into registration with the tack passage 51 of the separator. As already made plain, 65 the machine will continue to operate under

these conditions so long as the operator does nothing to vary the cycle. Operation in this manner, therefore, continues while the shoe is being lasted along one side of the forepart between the tip line and the line at the ball where the forward edge of the reinforcing material 152 is encountered.

As already pointed out, the bunter gauge 17 should be maintained in retracted position in lasting the shank portion of the shoe 70 on account of the overhang of the last at this point and long tacks should be employed on account of the added thickness of the reinforcing material in the insole. In order to adapt the machine for thus operating, the treadle 144 is depressed and is held depressed while the lasting operation is continued along the shank. In the depression of the treadle the arm 130 is swung outwardly and maintained in the position shown in Fig. 9. In this movement the hook link 136 is moved toward the right so that it engages the pin 62 on the bell crank lever 63 and holds the latter in the same position as it formerly occupied and as shown in Fig. 5, that is to say, 80 at the limit of its movement in a counter clockwise direction with the bunter gauge 17 in retracted position.

The movement of the arm 130 also rocks the swing piece 100 and the ratchet disk 80 85 as above, so that in the ensuing reciprocation of the slide 43 the ratchet disk is again carried one-sixth of a revolution forward and the yoke 74 is moved to the outer limit of its horizontal oscillation, swinging the yoke 70-71 so that the intermediate portion thereof is carried away from the arm 64 on the lever 63. The latter, however, is now prevented from following the movement of the yoke by the action of the hook link 136. The 90 swinging movement of the yoke 70-71 also swings the arm 56 in a clockwise direction advancing the link 52 and swinging the raceway to bring the long track channel 20 into operative position. So long as the operator maintains the treadle 144 in depressed position, the cycle of the machine is repeated, long tacks being delivered and the bunter gauge 95 being held in retracted position.

If the operator should depress the treadle 144 too early in the cycle of the machine, that is to say, while the slide 43 is advanced from its initial position, the flange of the safety lever 116 will prevent movement of the swing piece 100 by standing in front of the dog 115 which is mounted therein. Under these circumstances, depression of the treadle and movement of the arm 130 merely places the spring 103 under additional tension and moves the link 104 as permitted by its slot connection with the downwardly extending stud 102. Depression of the treadle, therefore, maintains the spring 103 under tension and when the slide 43 is eventually moved to its initial position the safety lever 116 is 120 125 130

moved to release the swing piece 100 and its movement then takes place with the results above set forth.

When the operator has completed lasting 5 the shank and reaches the heel-seat portion of the shoe, it is desirable to advance the bunter gauge into operative position but to maintain the machine in condition for delivering long tacks on account of the added thickness 10 of the counter and the reinforcing material in the insole. In order to organize the machine for operating in this manner, it is necessary merely to release the treadle 144, whereupon the link 104 is moved to the inner 15 limit of its travel, lost motion occurring between the slot in the link and the stud 102. The hook link 136 is also moved toward the left at this time and is thrown outwardly and disengaged from the pin 62 by the cooperation 20 of the inclined surface of its throat with the curved surface of the yoke 70-71 between the ears 138. The bell crank lever 63 is thus disengaged and is free to be swung in a clockwise direction under the actuation of the tension spring 61. The bell crank lever 93 is thereupon swung by the link 95 in the direction to advance the bunter gauge, the forward movement of the latter being limited by the engagement of the arm 64 on the lever 25 with the inner face of the yoke 70-71. Fig. 11 of the drawings illustrates the machine organized for operating in the manner above explained.

Upon reaching the shank on the second side 30 of the shoe, the operator may again retract the bunter gauge without disturbing the delivery of long tacks by depressing and holding the treadle 144. This initiates the movement of the ratchet disk 80 as above and causes the 35 power-operated inward movement of the yoke 74, during which the bell crank lever 63 is rocked in a counter clockwise direction by the engagement of the yoke 71 with the arm 64 so that the bunter gauge is 40 withdrawn. As the treadle is maintained depressed, the swing piece 100 is held at the limit of its movement in a counter clockwise direction and the dog 110 is positioned to engage the roller 112 on the arm 56. The link 52 is, therefore, locked in extended 45 position and the raceway maintained in position to deliver long tacks from the raceway channel 20.

Upon leaving the reinforced shank portion 50 of the shoe and arriving at the forepart on the second side where short tacks are again desired, the operator will release the treadle, whereupon the swing piece 100 is permitted to move and release the roll 112 on the raceway shifting arm 56, so that under the actuation 55 of the spring 61 the raceway is shifted again to the position shown in Fig. 5 of the drawings, wherein the raceway channel 19 for short tacks becomes operative, and since 60 the yoke 74 is moved from the position shown

in Fig. 11 to that shown in Fig. 5, the yoke 70-71 now occupies a position to hold the bunter operating lever 63 in bunter-retracting position.

Finally, in lasting about the toe portion of 70 the shoe, the treadle is again depressed and released, whereupon both the raceway and bunter are shifted and the machine is organized for driving long tacks with the bunter advanced.

It will be apparent that the machine may be employed in lasting in any order or progression desired and that whether moving from heel to shank or from forepart to shank the appropriate position of the raceway and edge gauge for shank lasting is obtained by depressing and holding the treadle 144. It should be further noted that after shank lasting 75 succeeding forepart lasting the release of the treadle positions the parts for heel-seat 80 lasting, and that after shank lasting succeeding heel-seat lasting the release of the treadle 85 positions the parts for forepart lasting. In other words, the organization of the machine is so controlled that without special attention 90 on the part of the operator, the machine adapts itself in anticipation of the lasting conditions desired in the part of the shoe about to be presented.

It will be noted that the spring 59, in addition to its function of maintaining the yoke 54 in contact with the screw 55 in the raceway shifting mechanism, provides relief in the train of mechanism in case the race-way 95 should become jammed, as by a misplaced tack, when the arm 56 is moved positively by the yoke 70-71 in shifting the raceway from long to short tack position. Under these 100 circumstances, the spring will yield and permit lost motion to occur between the yoke 54 and the screw upon which it is suspended. Inasmuch as the shifting of the raceway from 105 short to long tack position is effected under the actuation of the spring 61, there is no danger of breakage if the raceway should 110 be jammed against movement in that direction.

Having thus described my invention, what I claim as new and desire to secure by Letters Patent of the United States is:

1. A lasting machine having tacking mechanism including raceways for presenting long or short tacks, power-operated raceway shifting mechanism, gauges including a bunter gauge, means tending at all times to advance said bunter gauge, and means under the control of the operator for holding the bunter in retracted position during the operation of the raceway shifting mechanism in moving the raceways from short to long 120 tack position.

2. A lasting machine having tacking mechanism including raceways movable for presenting long or short tacks, power-operated means for shifting the raceways from 125

short to long tack position, gauges including a bunter gauge movable from inoperative to operative gauging position, means connected to said power-operated means yieldingly tending to shift the bunter gauge into operative position, and means under the control of the operator for holding the bunter in inoperative position while permitting the raceways to be shifted to long tack position.

10 3. A lasting machine having tacking mechanism including raceways movable for presenting either long or short tacks, power-operated means for shifting the raceways from short to long tack position, gauges including a bunter gauge movable to and from operative position, and a controlling device movable to cause the shifting of the raceways alternately from short to long tack position so connected to said bunter as to delay the positioning of the latter while held by the operator in a predetermined position.

4. A lasting machine having tacking mechanism including raceways movable for presenting either long or short tacks, raceway shifting mechanism, gauges including a movable bunter gauge, a treadle for controlling said raceway shifting mechanism, a spring-operated member for advancing the bunter, and connections between said member and treadle whereby said member may be maintained in bunter retracting position while the treadle is held depressed by the operator, thereby organizing the machine to last with long tacks while the bunter is retracted.

35 5. A lasting machine having tacking mechanism including raceways movable for presenting either long or short tacks, raceway shifting mechanism, gauges including a movable bunter gauge, a treadle for controlling said raceway shifting mechanism, a spring-operated lever connected to the bunter and tending to move it to operative position, and connections between said lever and treadle whereby depression of the latter holds said lever in bunter-retracting position.

6. A lasting machine having raceways movable for presenting either long or short tacks, raceway shifting mechanism, a movable bunter gauge, a spring-operated lever connected to the bunter and tending to move it to operative position, power-operated means connected to said raceway shifting mechanism for swinging said lever to retract the bunter, a treadle for controlling said shifting mechanism, and connections between said lever and treadle for holding said lever in bunter-retracting position.

7. A lasting machine having raceways movable for presenting either long or short tacks, lasting and tacking instrumentalities associated therewith, gauges including a movable bunter gauge, power-operated mechanism for moving the raceways from one position to another in timed relation to the operation of the lasting and tacking instru-

mentalities, a controlling device for the raceways and bunter gauge, and safety means for preventing the action thereof except when the tacking instrumentalities are properly positioned.

70 8. A lasting machine having raceways movable for presenting either long or short tacks, tacking mechanism associated therewith, a movable bunter gauge, power-operated means for shifting the raceways from long to short tacks and shifting the bunter gauge into and out of operative position without interrupting the normal lasting cycle of the machine, and means under the control of the operator for determining whether or not the bunter will be shifted and for initiating the shifting of the raceway from one position to another.

85 9. A lasting machine having a raceway movable to present either long or short tacks, power-operated means acting under the control of the operator to effect the movement of the raceway to its alternate positions, a movable bunter gauge, means connecting the bunter gauge and the power-operated means for moving the same, and a single device for controlling the action of said power-operated means so that either short or long tacks may be presented and the bunter gauge may be held in inoperative position or allowed to shift to operative position.

90 10. An organized lasting machine of the hand method type, having a raceway for long and short tacks, a reciprocating actuator, means under the control of the operator for connecting said raceway and actuator to move the raceway to its alternate positions, and means under the control of the operator for temporarily holding said raceway against the action of said reciprocating actuator.

105 11. A lasting machine having a raceway movable to deliver either long or short tacks, a bunter gauge movable to and from operative position, a lever connected to said raceway for shifting the same, a lever connected to said bunter for the same purpose, a common spring actuating both levers, and means arranged to be positioned by the operator for holding either lever against movement.

110 12. A lasting machine having lasting and tacking instrumentalities and power-actuated operating mechanism therefor, a raceway movable to present either long or short tacks, raceway shifting mechanism acting automatically to shift the raceway alternately from one position to the other in one cycle of the machine, said mechanism being under manual control as to its operation in any selected cycle, and separate means also under manual control for delaying the shifting of the raceway during any desired number of lasting cycles.

125 13. A lasting machine having lasting and tacking instrumentalities and power-actuated operating mechanism therefor, a race-

- way movable to present either long or short tacks, a bunter gauge movable from operative to inoperative position, shifting mechanism acting automatically to shift the bunter alternately from one position to the other in a cycle of the machine, said mechanism being under manual control as to its operation in any selected cycle, and separate means also under manual control for delaying the shifting of the bunter during any desired number of lasting cycles and then permitting it to shift.
14. A lasting machine having lasting and tacking instrumentalities, power-operated actuating mechanism therefor, a raceway movable to present either long or short tacks, gauges including a bunter gauge movable from retracted to advanced position, treadle controlled means for connecting the raceway and bunter to said power-operated actuating mechanism in any selected cycle of the machine to effect the shifting of the raceway and bunter to new positions constructed and arranged to delay the shifting of either member for any desired number of lasting cycles.
15. A lasting machine having lasting and tacking instrumentalities, power-operated actuating mechanism therefor, a raceway movable to present either long or short tacks, gauges including a bunter gauge movable from retracted to advanced position, and treadle-controlled means for connecting the raceway and bunter to said actuating mechanism in any selected cycle of the machine to effect the shifting of the raceway and bunter from one to the other of their respective positions and including means for latching the bunter under tension in retracted position for any desired number of lasting cycles and for releasing the bunter to permit it to shift.
16. An organized lasting machine of the hand method type having a power-driven actuator, a raceway movable to present either long or short tacks, gauges including a bunter gauge movable between retracted and advanced positions, lost motion connections between said actuator on the one hand and said raceway and bunter on the other hand, treadle-controlled means for causing a movement of said actuator in any selected cycle of the machine constructed and arranged to delay its effective action upon the raceway or bunter for any desired number of lasting cycles.
17. An organized lasting machine of the hand method type having a raceway movable to present either long or short tacks, gauges including a bunter gauge movable between retracted and advanced positions, a driven actuator, an oscillatory yoke arranged to be connected thereto for movement in any selected cycle of the machine and having lost motion connections with both the bunter and the raceway which are under the control of the operator.
18. An organized lasting machine of the hand method type having a raceway movable to present either long or short tacks, gauges including a bunter gauge movable between retracted and advanced positions, a driven actuator, an oscillatory yoke arranged to be moved thereby in any selected cycle of the machine, a bunter shifting member arranged to be moved to bunter-retracting position by said yoke, and spring means under the control of the operator for advancing said bunter independently of said yoke.
19. An organized lasting machine of the hand method type having a raceway movable to present either long or short tacks, gauges including a bunter gauge movable between retracted and advanced positions, a driven actuator, an oscillatory yoke arranged to be moved thereby in any selected cycle of the machine, a bunter shifting member arranged to be moved by the yoke to bunter-retracting position, spring means for moving the bunter shifting member to bunter-advancing position, and treadle means for preventing the movement thereof during any desired number of lasting cycles.
20. An organized lasting machine of the hand method type having a raceway movable to present either long or short tacks, gauges including a bunter gauge movable between retracted and advanced positions, a driven actuator, an oscillatory yoke arranged to be moved thereby in any selected cycle of the machine, a bunter shifting member arranged to be moved by the yoke to bunter-retracting position, a raceway shifting member arranged to be moved by the yoke to long tack position, and spring means under the control of the operator for advancing said bunter and shifting the raceway to short tack position independently of said yoke.
21. An organized lasting machine of the hand method type having a raceway movable to present either long or short tacks, gauges including a bunter gauge movable between retracted and advanced positions, power-actuated operating mechanism including a member movable in one direction to shift the raceway to long tack position and in the other to retract the bunter, and means under the control of the operator for connecting said member to said operating mechanism in any selected cycle of the machine.
22. An organized lasting machine of the hand method type having a raceway movable to present either long or short tacks, gauges including a bunter gauge movable between retracted and advanced positions, power-actuated operating mechanism including a member movable in one direction to shift the raceway to long tack position and in the other to retract the bunter, spring operated means for shifting the raceway to short tack

position and for advancing the bunter, and treadle controlled means for connecting said member to said operating mechanism in any selected cycle of the machine.

5 23. A lasting machine having a raceway movable between long and short tack positions, a gauge movable between retracted and advanced positions, power-actuated operating mechanism including a member arranged to be moved in any selected cycle of the machine to shift the raceway to long tack position, spring means for advancing said gauge, and treadle controlled means for restraining said gauge, whereby the lasting operation may be carried out with long tacks and a retracted gauge.

10 24. A lasting machine having a raceway movable between long and short tack positions, a gauge movable between retracted and advanced positions, a member arranged to be moved by power in alternate cycles of the machine to control the shifting of the raceway to short tack position and to retract the gauge, and a swing piece under treadle control constructed and arranged to be positioned to delay the shifting of the raceway whereby the lasting operation may be continued with long tacks and a retracted gauge.

15 25. A lasting machine having lasting instrumentalities, a gauge movable between retracted and advanced positions, a raceway movable between long and short tack positions, said machine being organized to operate with the raceway in short tack position and the gauge retracted, and means under the control of the operator for temporarily holding the gauge retracted and causing the raceway to assume its long tack position, said means upon being released acting to organize 20 the machine to operate with the raceway in long tack position and the gauge advanced.

25 In testimony whereof I have signed my name to this specification.

THOMAS H. SEELY.
